US00D590410S

(12) **United States Design Patent**
Wall et al.

(10) Patent No.:

US D590,410 S

(45) Date of Patent: ** Apr. 14, 2009

- (54) **USER INTERFACE FOR SOFTWARE PROJECT SYSTEM FOR COMPUTER DISPLAY**

(75) Inventors: **Matthew B. Wall**, Cambridge, MA (US); **Timothy R. Wall**, Cambridge, MA (US); **Andrew Aucott**, Eaglescliffe (GB)

(73) Assignee: **Oculus Technologies Corporation**, Boston, MA (US)

(**) Term: **14 Years**

(21) Appl. No.: **29/286,806**

(22) Filed: **May 18, 2007**

(51) **LOC (9) Cl. 14-04**

(52) **U.S. Cl. D14/486**

(58) **Field of Classification Search .....** D14/485-95; D18/24-33; D19/6, 52; D20/11; D21/324-33; 715/700-867, 973-77

Primary Examiner—Melanie H Tung

(74) *Attorney, Agent, or Firm*—Hamilton, Brooks, Smith & Reynolds, P.C.

CLAIM

The ornamental design for a user interface for software project system for computer display, as shown and described.

DESCRIPTION

The article of manufacture is a computer software program used for managing software design and configurations.

The single FIGURE is a front view of a user interface for a software project system for a computer display showing our new design.

The broken line drawing of a computer display forms no part of the claimed design.
